Primary Examiner — Rachel A. Voorhies

(57) **CLAIM**

The ornamental design for an electronic display for a wearable device presenting a graphical user interface, as shown and described.

DESCRIPTION

FIG. 1 is a front view of a first image of an embodiment of an electronic display for a wearable device presenting a graphical user interface, showing our new design;

FIG. 2 is an enlarged front view taken from FIG. 1;

FIG. 3 is a front view of a second image thereof;

FIG. 4 is an enlarged front view taken from FIG. 3;

FIG. 5 is a front view of a first image of another embodiment of an electronic display for a wearable device presenting a graphical user interface, showing our new design;

FIG. 6 is an enlarged front view taken from FIG. 5;

FIG. 7 is a front view of a second image of said another embodiment; and,

FIG. 8 is an enlarged front view taken from FIG. 7.

The broken line showing of the electronic display for a wearable device presenting a graphical user interface is for the purpose of illustrating portions of the electronic display for a wearable device presenting a graphical user interface and forms no part of the claimed design.

The dot-dash broken line encircling the enlarged portions forms no part of the claimed design.

The appearance of the graphical user interface transitions sequentially between the images shown in FIGS. 1 and 3, FIGS. 2 and 4, FIGS. 5 and 7, and FIGS. 6 and 8. The process or period in which one image transitions to another forms no part of the claimed design.

1 Claim, 8 Drawing Sheets
